UNITED STATES PATENT OFFICE.

WILLIAM E. HINGSTON, OF BUFFALO, NEW YORK, ASSIGNOR TO HIMSELF,
W. M. CITERLEY, AND GOODRICH J. BOWEN, OF SAME PLACE.

FLY-POISON PLATE.

SPECIFICATION forming part of Letters Patent No. 239,781, dated April 5, 1881.

Application filed April 15, 1879.

To all whom it may concern:

Be it known that I, WILLIAM E. HINGSTON, of the city of Buffalo, in the county of Erie and State of New York, have invented an Improved 5 Fly-Poison Plate, fully set forth in the following specification and accompanying drawings, in which—

Figure 1 is a plan or face view of the plate, and Fig. 2 a cross-section through the center. 10 The object of this invention is to produce a fly-poison device that is safe, clean, always ready, and complete in itself for all the purposes necessary to its use; and it consists of a plate of any suitable material—such as porcelain, wood, paper, sheet metal, or its equivalent—which may have the words “fly-poison” 15 or similar words placed on it in a suitable place to indicate its character, having an absorbent disk forming a part of the bottom of the plate or fastened thereto, and over which a label may be placed, the whole forming a plate adapted to receive a sufficient quantity 20 of water when required for use.

A represents the plate; D, a disk or layer

of absorbent material to receive the poison. 25 It is made of thick absorbent paper; but porous earthenware, wood, or any other material that will absorb and hold the poison will answer the purpose.

B represents the upper surface of the rim, 30 and C is the advertising disk or slip placed over the poison material, to which it is pasted or otherwise fastened. The outer edge of C, (shown by dotted lines,) may be cemented or otherwise fastened to the plate, so that the 35 water will not cause its separation.

Any of the well-known poisons for the purpose may be used.

I claim—

The within-described fly-poison device, consisting of a plate having a disk of absorbent material containing poison, forming a part of the bottom of the plate or fastened thereto, as set forth. 40

WILLIAM E. HINGSTON.
